UNITED STATES PATENT OFFICE.

DON A. DE NISI, OF FORESTVILLE, ASSIGNOR OF ONE-HALF TO EDWARD BARNARD, OF ROME, NEW YORK.

CHECKREIN-BAR.

SPECIFICATION forming part of Letters Patent No. 375,477, dated December 27, 1887.

Application filed October 7, 1887. Serial No. 251,742. (No model.)

To all whom it may concern:

Be it known that I, DON A. DE NISI, a citizen of the United States, residing at Forestville, in the county of Chautauqua and State of New York, have invented a new and useful Improvement in Check-Bars, of which the following is a specification.

My invention relates to an improvement in check-bars or spreaders for harness; and it consists in the construction and arrangement of the parts thereof, which will be more fully hereinafter described, and pointed out in the claims.

In the accompanying drawings, wherein like letters of reference indicate similar parts in the several views, Figure 1 is a perspective view of my improved check-bar. Fig. 2 is an elevation thereof.

A represents a horizontal bar, which is formed with reduced ends a^1 , having suitable ornamental knobs, a^2 , and loops a^3 . The central portion of the bar is formed with a swelled loop, a^4 , having a stationary perpendicular bar, a^5 . The parts as just described are all formed integral and at one operation. A strap, B, is passed around the bar a^4 in the loop a^3 , and is sewed at its central portion to form the loops v^1 , v^2 , the loop v^1 engaging with the bar a^5 and the loop v^2 being free for attachment to the check-hook.

It will be understood that the ends of the

checkreins will be secured to the loops a^2 , and the loop v^2 of the strap B secured in connection with the check-hook. The strap B, mounted in connection with the bar A, as 35 above described, allows the animal to move his head laterally. The ends of the bar taper somewhat from the swell-loop in the center toward the loops a^2 . By the use of the leather strap B a durable and serviceable connection 40 is obtained, which at the same time is convenient in attaching to the check-hook. This construction also permits of a ready attachment of the bar to any style of check-hook.

The utility of my device being obviously 45 apparent, it is unnecessary to further enlarge upon the same herein.

Having thus described my invention, what I claim as new is—

1. A horizontally-formed check-bar or 50 spreader having a central swelled loop inclosing a bar for the attachment of the strap.

2. A check-bar or spreader having the central loop inclosing a bar for the attachment of a strap, and the check-attaching loops a^2 . 55

In testimony that I claim the foregoing as my own I have hereto affixed my signature in presence of two witnesses.

DON A. DE NISI.

Witnesses:

AMOS DENISEN,
D. H. FILDEN.

Correction in Letters Patent No. 375,477.

It is hereby certified that the name of the patentee in Letters Patent No. 375,477, granted December 27, 1887, for an improvement in "Checkrein-Bars," should have been written and printed *Don A. De Nise* instead of "Don A. De Nisi," and that the proper correction has been made in the files and records of the case in the Patent Office, and should be read in the said Letters Patent that the same may conform thereto.

Signed, countersigned, and sealed this 10th day of January, A. D. 1888.

[SEAL.]

Countersigned:

BENTON J. HALL,

Commissioner of Patents.

D. L. HAWKINS,
Acting Secretary of the Interior.
